UNITED STATES PATENT OFFICE.

GEORGE A. PETERS, OF HUTCHINSON, MINNESOTA.

ADJUSTABLE PARTITION FOR STOCK-CARS.

No. 888,844.

Specification of Letters Patent.

Patented May 26, 1908.

Application filed December 27, 1907. Serial No. 408,327.

To all whom it may concern:

Be it known that I, GEORGE A. PETERS, a citizen of the United States, residing at Hutchinson, in the county of McLeod and State of Minnesota, have invented certain new and useful Improvements in Adjustable Partitions for Stock-Cars; and I do hereby declare the following to be a full, clear, and exact description of the invention, such as will enable others skilled in the art to which it appertains to make and use the same.

My invention relates to stock cars and has for its object to provide an improved adjustable partition for separating the car body into different compartments.

To the above ends the invention consists of the novel devices and combinations of devices hereinafter described and defined in the claims.

It is a well known fact that in shipping stock it is very often desirable to put cattle, hogs or sheep, or sometimes all three, in the same car; and, when this is done, it is necessary to keep the different kinds of stock separated.

My invention provides a simple and efficient car partition which is adjustable so as to properly divide up the space of the car for mixed shipment of stock; and, furthermore, provides a simple means for opening a part of the partition so that the stock may be driven from the one compartment to the other, or an attendant may readily pass from the one compartment to the other.

The invention, in its preferred form, is illustrated in the accompanying drawings, wherein like characters indicate like parts throughout the several views.

Referring to the drawings, Figure 1 is a vertical section taken transversely through the intermediate portion of the body of a stock car of standard construction, and illustrating one of my improved adjustable partitions applied thereto. Fig. 2 is a detail in perspective, showing one of the couplings for connecting one of the gates of the partition to the adjacent side of the car body; and Fig. 3 is a vertical section taken longitudinally through the intermediate portion of the car body, approximately on the line $x^3 x^3$ of Fig. 1, and showing the adjustable partition folded and secured in an inoperative position near the roof of the car.

The car body, which is indicated as an entirety by the numeral 1, is of the usual or any suitable construction, and, to the inner sur-

faces of its sides, are attached longitudinally extended upper and lower anchoring rails or strips, preferably in the form of iron pipes 2 which are rigidly secured to the said car 60 sides, by staples 3. These so-called anchoring rails or strips may, however, take various forms so far as the broad idea of my invention is concerned.

Extending longitudinally of the car body, 65 close to the roof thereof, is a pair of guide rails, shown as in the form of heavy iron rods 4. These rods will be rigidly secured to the ends of the car body, and, when desired, may be secured to the car roof at suitable intermediate points.

The adjustable partition, as preferably constructed, is made up of three sections, to-wit, an intermediate body section and a pair of reversely projecting gate sections. The 75 intermediate body section, as shown, is made up of a pair of vertically extended laterally spaced posts 5, an upper tie bar 6 and a multiplicity of vertically spaced partition bars 7, which latter tie together the lower portions 80 of said posts. The gates are each made up of a multiplicity of parallel gate bars 8, each pivotally connected at 9 to the intermediate portion of a partition bar 7, and pivotally connected at their outer ends to a vertically 85 extended gate post 10.

To the upper end of each partition post 5 is rigidly secured a metal cap 11 having an upwardly projecting eye 11^a, to which is loosely connected a yoke-like bracket 12 that embraces the corresponding guide rail 4 and is provided with a sheave or wheel 13 that runs upon said rail. The intermediate portions of the gate bars 8 work between and are guided by the partition posts 5 and vertically extended guide rods 14 that are secured at their upper and lower ends to the upper and lower ends of the corresponding posts 5.

Mounted to slide vertically upon each post 100 5 is a so-called anchoring rod 15 provided, as shown, at their upper ends with hand-pieces 16 and having sharpened lower ends 15^a, which latter are adapted to be placed into the car floor to assist in securing the adjustable partition in any set position.

Rigidly secured to the outer end of each gate post 10 is a pair of vertically extended coupling yokes 17. On the vertically extended portion of each coupling yoke 17 a 110 pronged coupling head 18 is pivotally and slidably mounted. These pronged coupling

heads 18 are adapted to embrace the upper and lower anchoring pipes 2 and are adapted to be secured in different positions thereon by means of pins or bolts 19 which, in turn, 5 are adapted to be passed through perforations in the prongs of said heads 18 and through any of a series of perforations 20 in said pipes. As shown, the pins 19 are connected to the yoke 17 by means of short 10 chains 21 which prevent the same from being lost or displaced when not in use.

In Fig. 1 the adjustable partition is shown as anchored by one of the sharp pointed anchoring rods 15, and the gate at the right is 15 shown as secured to the coöperating anchoring pipes 2, while the gate at the left is shown as raised into an inoperative position, so as to permit stock to be driven from the one side to the other of the partition, or to permit 20 an attendant to readily pass from the one side to the other of said partition. Of course, when the partition is in position to divide the different kinds of stock, both of the gates will be secured in lowered positions.

25 The coupling heads 18 are mounted for both pivotal and sliding movements on the yoke 17, so that they may better adapt themselves to any inaccuracies in the spacing of the coöperating posts 2, or to the varying 30 positions of the partition itself, it being, of course, understood that said partition will not, in its different adjustments, always stand in exactly the same relation to the anchoring pipes.

35 As is evident, the partition above described may be very quickly adjusted to different positions and in every way is a very easily operated and highly satisfactory device for the purposes had in view.

40 When it is not desired to use the partition, both gates are moved into inoperative or folded positions, as indicated at the left in Fig. 1, and then the folded partition is turned pivotally upward against the rails 4 and the 45 free end portion thereof is secured to said rails by suitable devices, such, for instance, as by hooks 22 on said rails, that engage with eyes 23 secured to the lower ends of the posts 5, as shown in Fig. 3. When the gate is thus 50 secured in its raised or inoperative position it will be entirely out of the way and may be slid upon the rails 4 to any desired position.

The device above described may, at small 55 cost, be easily applied to stock cars of standard construction. The utility thereof will be readily appreciated by all persons familiar with the shipment of stock.

What I claim is:

60 1. A partition for car bodies comprising an intermediate body portion and adjustable gates projecting from the opposite sides thereof, each gate comprising a multiplicity of parallel bars pivotally connected at their inner ends to the intermediate portion of said

body portion for movement in a vertical 65 plane, and gate posts pivoted to the outer ends of said bars and connecting the same for parallel swinging movements, substantially as described.

2. The combination with a car body having longitudinally extended guide rails secured in the vicinity of the roof thereof and having longitudinally extended anchoring bars secured to the inner surfaces of the sides thereof, of an adjustable partition comprising 70 an intermediate body section suspended from and mounted to travel on said rails, and adjustable gates pivotally connected to the intermediate portion of and projecting from the opposite sides of said body section for 75 movements in a vertical plane and provided at their free edges with means for detachably securing the same to the said anchoring bars, substantially as described.

3. The combination with a car body, of an 80 adjustable partition extended from the upper portion of said car body with freedom for traveling movements longitudinally thereof and provided with vertically movable anchoring rods having sharp lower ends adapted 85 to engage the floor of the car, substantially 90 as described.

4. The combination with a car body having 95 perforated anchoring bars secured to the inner surfaces of the sides thereof, of an adjustable partition comprising an intermediate body section and gates projecting from the opposite sides thereof, each gate comprising parallel bars and a gate post connecting the free ends thereof, means supporting 100 said intermediate gate section from the car body with freedom for traveling movements longitudinally thereof, pronged coupling heads adjustably connected to the outer edge portions of said gates, and pins for detachably connecting said coupling heads to 105 said perforated anchoring bars, substantially as described.

5. In an adjustable partition for car bodies 110 the combination with an intermediate body section having vertically extended posts and vertically extended guide rods secured at their upper and lower ends to said posts, of gates made up of parallel bars and posts pivotally connecting the free ends thereof, 115 which gate bars work between the coöperating posts and guide rods of said intermediate body section and are pivotally connected to the latter at their inner ends, and means applied to the outer edge portions of said gates 120 for detachably securing the same to the sides of a car, substantially as described.

In testimony whereof I affix my signature in presence of two witnesses.

GEORGE A. PETERS.
